UNITED STATES PATENT OFFICE.

BENJAMIN S. GALLUP, OF HAMMOND, LOUISIANA.

CAR-LOAD BRACE.

1,187,898.

Specification of Letters Patent. Patented June 20, 1916.

Application filed August 2, 1915. Serial No. 43,278.

To all whom it may concern:

Be it known that I, BENJAMIN S. GALLUP, a citizen of the United States, residing at Hammond, in the parish of Tangipahoa and State of Louisiana, have invented 5 certain new and useful Improvements in Car-Load Braces, of which the following is a specification.

This invention relates to certain new and 10 useful improvements in car load braces, and particularly pertains to a device for retaining stacked containers such as fruit crates, boxes and the like, in position during transportation.

15 It is the primary object of this invention to provide a device of the character above mentioned which will afford fragile commodities efficient protection against breakage, or other damage, due to relative shifting 20 of the containers resulting primarily from compression thereof while the same are being transported.

Another object is to provide a device of 25 this character which will automatically compensate for any slack in the load incident to the jarring and shaking thereof while in transit.

A further object is to provide a device of 30 this character, which is so constructed and arranged that it may be adjusted to any desired position in the car against the containers packed therein, and securely fastened to retain the containers in proper position.

35 Another object is to provide novel supporting and securing means for the several sections of the device.

A further object is to provide a device of 40 this character, wherein each tier of crates or boxes in the load, is braced independent of the adjacent tiers, thereby affording proper support to each individual tier-unit. Proper bracing of only a portion of the load is thereby avoided and compensation made 45 for any unevenness that may occur in loading or any variance in the size of the crates.

With the above and other objects in view 50 my invention consists of the parts, and the construction and combination of parts, hereinafter more fully described and claimed, reference being made to the accompanying drawing, in which:—

55 Figure 1 is a longitudinal sectional view of a portion of a refrigerator car, showing the device in operative relation to a load of fruit crates; Fig. 2 is a cross-sectional view

of a car taken on line 2—2 of Fig. 1, showing in front elevation, a plurality of the braces in position for use; Fig. 3 is an enlarged side elevational view of one of the 60 adjustable brace members, showing in detail, the spring take-up devices and the floor anchor or hinges, attached respectively to the upper and lower extremities of said brace member; and Fig. 4 is a perspective 65 view of the same.

Referring to the accompanying drawings, wherein similar reference characters designate corresponding parts, throughout the several views, 1 designates suitable rails or 70 tracks mounted within the car adjacent the ceiling thereof, on each of which rails, dogs 2 and 3 are slidably and adjustably mounted. The supporting rails 1 are held suspended adjacent the ceiling by means of 75 supporting brackets 4, secured to the extremities thereof, said rails being of sufficient length to extend a substantial distance toward the ends of the car to each side of the center thereof.

80 Interposed between the main dog 2 and the take-up or spring dog or lever 3, is a spiral spring 5, said spring being attached to dog 2 at a point immediately beneath the rail 1, and the dog 3 at its lower extremity 85 by means of suitable links 5^a, passing through perforations formed in the dogs or levers. The spiral spring 5 is of sufficient strength to force dog 3 to maintain a rigid and positive grip upon the rod 1 when 90 said spring is under tension, as is the case when the brace is operatively positioned with reference to the load.

95 For holding the spring dog 3 more firmly in place when once adjusted, it may be provided, if desired, though the same is not essential, with additional locking means, as for instance set screw 15, adapted to contact firmly with rod 1.

100 The main dog is connected to the brace member 6 by means of interposed links or chain section 7, one end of the chain being connected to the lower end of dog 2, while the opposite end is secured to an eye bolt 8 mounted in the upper end of the brace member or main lever 6.

105 The lower portion of each brace 6 is secured to the floor when the device is in use by means of a hinge, one member 9 being secured to the outer face of the lower 110 end of the brace, while the opposite member 10 is secured to the floor. Member 10 is

preferably formed with a spur 11 extending downwardly therefrom to facilitate the initial positioning of the brace, said member being likewise provided with one or more holes 12 through which nails may be driven. The said member 10 is curved upward slightly at its outer end in order to facilitate the removal of the device when not in use.

- 10 A hook 13 is attached to each brace 6 as a means of suspending the brace, when the same is free, from rail 1 in a horizontal position adjacent the car ceiling, this being the position in which they are placed when 15 not in use and free cargo space is desired. Similar hooks 14 are secured to the car ceiling directly above each supporting rod about midway the length of the car, said hooks being adapted to engage their corresponding rods and prevent sagging and 20 springing thereof when the braces are hung thereon.

In the operation of my invention, a series 25 of tiers or stacks of containers are loaded and arranged in the car in the usual manner as illustrated in Figs. 1 and 2. The tiers or stacks having been arranged in rows extending laterally across, and longitudinally of, the car, and the desired number having 30 been placed in one end thereof, the hooks 13 are disengaged from rails 1, and the braces 6 lowered and positioned firmly against the faces of the crates composing the outermost tier, each individual brace 35 engaging its corresponding tier. The lower ends of the braces, as hereinbefore explained, are secured in this position by means of the hinges and fastening means driven through the holes 12 therein.

- 40 Braces 6, being securely pivoted at their lower extremities, are forced back, one at a time, and secured, each on its individual supporting rail and against its corresponding tier, by spacing the spring take-up dogs 45 3 such distances from the main dogs 2 as will be sufficient to place springs 5 under tension proportionate to the weight of the load carried. The spring 5, having been placed under tension through moving dog 50 3 away from the brace 6, will cause the dog to assume a rigid and positive grip upon its supporting rail, 1, due to the leverage which the recoil of the spring exerts upon said dog 3. The dog 3 may when once adjusted be secured by set screw 15. Thus it 55 may readily be seen that any slack occurring in the load incident to sudden movement or jerking of the car, will be quickly and positively taken up through the brace member 6 by virtue of its being connected at its upper end with dog 2 which in turn is continually drawn toward dog 3 by means of the tensioned spring connecting the same. There being provided a similar set of 60 65 braces in the other end of the car, held in

their horizontal position by means of hooks 13 and rails 1, the same may be lowered and allowed to rest temporarily against the braced load in order to allow the loading of the remainder of the cargo and the bracing thereof as hereinbefore explained.

When it is desired to release the braces from the load, the spring dogs 3 are loosened, thereby relieving the tension on the springs 5, and thus allowing the main dogs 75 2 to be moved forward until the braces are free. On the other hand the lower ends of the braces may be detached by forcing a pinch-bar or the like under the upturned end of plate 10 and thereby withdrawing 80 the fastening means.

In action when the load is compressed by jar or impact, brace 6 will follow it up and dog 2 will be drawn to a greater or less extent toward dog 3, thus maintaining 85 brace 6 in contact with the load. Should the load not expand, or in other words, re-assume its normal proportions after impact, brace 6 will securely hold the same; and in case the load should tend to expand, dog 2 90 will be rocked or drawn forward at its lower end by brace 6, thereby causing the dog to cramp or bind upon the track or rail 1 and consequently prevent outward movement of the brace 6.

The number of supporting rods or rails affixed to the ceiling will vary according to the number of crate tiers, taken crosswise of the car. Six rows or tiers of crates are shown in Fig. 2, this being the usual number 100 in shipping loads of crated produce. Directly above and parallel to each tier is a supporting rod with the accompanying bracing device attached thereto, the same being constructed and applied as hereinbefore described and explained.

Having thus described my invention, what I claim is:—

1. A device of the class described comprising the combination with a car, of a 110 plurality of load bracing members spaced laterally therein and adapted to be swung into and out of a substantially vertical position; tracks located in the upper portion of the car; and means interposed between 115 the tracks and the bracing members for drawing each of the members into binding relation with the load.

2. A device of the class described comprising the combination with a car, of a 120 plurality of load bracing members spaced laterally therein and adapted to be swung into and out of a substantially vertical position; means for pivotally securing the lower ends of said members to the car floor tracks 125 located in the upper portion of the car; individual suspension and clutch means connected to the upper extremities of the braces and movably mounted on said tracks; corresponding clutch members adjustably 130

- mounted on the tracks and adapted to engage therewith; and elastic tension means connecting the last named clutch members with the corresponding suspension and clutch means and serving through the latter to draw the bracing members against the load.
3. A device of the class described comprising the combination with a car; of a track extending longitudinally thereof; a load bracing element adapted to be swung into and out of a substantially vertical position; means for hinging the lower portion of the same to the floor of the car; and elastic tension and locking means movably mounted on said track and connected to the upper end of said bracing element whereby the same will maintain a constant pressure on the load of articles stacked within the car.
4. In a load binder, the combination of a car; a track or supporting rail located in the upper portion thereof; a load bracing member; means for securing the lower end thereof to the car floor; and an adjustable tension mechanism interposed between said track and the upper end of the bracing member and serving to draw said member against the load.
5. In a load binder, the combination of a car; a track or supporting rail located in the upper portion thereof; a load bracing member; means for securing the lower end thereof to the car floor; a clutch arm adjustably mounted on the rail; a second arm slidably mounted on the rail; a spring interposed between the lower end of the clutch arm and the upper portion of the said second arm; and a suitable connection between the lower end of said second arm and the upper end of the load bracing member.
6. In a device of the class described, the combination of a car; a rail located in the upper portion thereof; a load bracing member; means for securing the lower end of said member to the floor of the car in bracing relation to the load to be braced; and an automatic take-up interposed between the upper end of the bracing member and the rail, adapted as the load compacts under jar or impact, to draw and maintain the bracing member in close and binding relation with the load.
7. In a device of the class described, the combination of a car; a rail located in the upper portion thereof; a load bracing member; means for securing the lower end of said member to the car floor in bracing relation to the load to be braced; clutching means connected to the upper extremity of the bracing member and coacting with said rail; a member adjustably mounted on the rail and adapted to engage therewith; and elastic tension means connecting said member with the clutching means, and adapted as the load compacts under jar or impact, to draw the clutching means in the direction of the load and through said clutching means to maintain the bracing member in close and binding relation with the load.

In testimony whereof I have signed my name to this specification.

BENJAMIN S. GALLUP.
